F. E. KENNEY,
PORTABLE RECIPROCCABLE HYDRAULIC POWER DEVICE.
APPLICATION FILED FEB. 23, 1915.

1,195,141.

Patented Aug. 15, 1916.

UNITED STATES PATENT OFFICE.

FRANK E. KENNEY, OF PORTLAND, OREGON, ASSIGNOR OF FIVE-EIGHTHS TO DANIEL W. HOELBING, OF PORTLAND, OREGON.

PORTABLE RECIPROCABLE HYDRAULIC POWER DEVICE.

1,195,141.

Specification of Letters Patent. Patented Aug. 15, 1916.

Application filed February 23, 1915. Serial No. 10,162.

To all whom it may concern:

Be it known that I, FRANK E. KENNEY, a citizen of the United States, and a resident of Portland, county of Multnomah, and 5 State of Oregon, have invented a new and useful Improvement in Portable Reciprocable Hydraulic Power Devices, of which the following is a specification.

The object of my invention is to provide 10 a hand-operated portable hydraulic power device adapted for applying a pushing or a pulling force to any object.

My invention was especially designed for 15 the splitting of logs and stumps; but it may be effectively used for many other purposes besides.

The word hydraulic is to be understood as designating any suitable fluid. In most instances I prefer to use oil.

20 The details of construction of my hydraulic power device and its mode of operation will be more readily understood by having reference to the accompanying drawings as a part of this specification.

25 In such drawings, Figure I shows a side elevation of my hydraulic power device, the engine cylinder and the compensating cylinder being shown in longitudinal, vertical section. Fig. II is a top or plan view of my 30 device. Fig. II^a is a detail of construction showing the rear end of the engine cylinder; Fig. III is a left-end view of my device. Fig. IV is a vertical section taken on the broken line IV of Fig. IV^a. Fig. IV^b is a 35 section taken on the broken line IV^a of Fig. IV. Fig. IV^b is a sectional view similar to Fig. IV, but taken through the branch pipe 15 and showing the valve 30 in reverse position relative to the position of the 40 valve 30 in Fig. IV.

The construction and operation of my hydraulic power device is as follows: *k* is an engine cylinder, in which reciprocates the piston *u*' having a rod *u* projecting through 45 the stuffing-box 5. 1 is a compensating chamber mounted above and parallel to the engine cylinder *k*. The head-piece 7, for the outer ends of the engine cylinder and the compensating chamber may be an integral 50 casting as shown in Fig. 1. A duct 8 connects the outer ends of the engine cylinder and the compensating chamber. At the inner end of the compensating chamber 1 is provided a duct or port 9, which connects 55 with a transverse pipe 10, on one end of

which is mounted a funnel-shape tube 11, opening to the air for receiving the operating fluid, for which I preferably use oil, and also permitting the air to enter. A check-valve is to be understood as located at 60 12, which is adapted to admit fluid into the pipe 10, but prevents the emission of fluid from said pipe. The latter connects with a pipe 13, which has branches 14 and 15 connecting with the four-way valve 16, operated by its handle 17. The construction of the valve 16, is shown in Fig. IV and is of the spigot type, its spigot 18 being provided with radial alined ports 19 connecting with a downwardly extending port 20, leading to 70 the bottom of the valve chamber 21. The bottom of the valve-chamber is connected by a duct 22 with the force-pump 23, operable by its handle 24. The valve 16 is further connected by pipes 25 and 26, with a 75 pipe 27, which is connected by a branch 28 to the port 29, at the inner end of the engine cylinder *k*. When the spigot 18 is in one position, as shown in Fig. IV^a, the alined ports 19 connect the pipes 15 and 25, and 80 when said spigot is turned through an angle of 90 degrees, the ports 19 will connect the pipes 14 and 26. The flow of the operating fluid through each of the pipes 14, 15, 25 and 26 is controlled by a check-valve 30, as 85 illustrated in Figs. IV and IV^a. The valves 30 in pipes 14 and 25 open toward the valve 16, as shown in Fig. IV, and the valves 30 in pipes 15 and 26 open away from the valve 16, as shown in Fig. IV^b. The check valves 90 are so arranged that by the proper adjustment of the valve 16, the fluid may be pumped from the outer end of the engine cylinder, through the compensating chamber 1, into the inner end of the engine-cylinder, 95 thus forcing the piston in the latter forward, or vice-versa, as required. The purpose of the compensating chamber is apparent from an inspection of Fig. I. Since the piston rod *u* takes up a portion of the 100 space of the engine cylinder on the outer or forward side of the piston *u*', when the piston is moved inward the surplus operating fluid so displaced must be taken care of, and therefore is held in storage, as it were, in 105 the compensating chamber 1. The piston *u*' is retracted by pumping the fluid into the forward end of the cylinder *k*. When the piston *u*' has been projected forward the compensating chamber 1 will be only 110

partially full, owing to the fact that more fluid is pumped out of it into the rear end of the cylinder, *k*, than is carried into said chamber. Conversely, when the piston is 5 retracted, the compensating tank will fill owing to the fact that more fluid is pumped into it than it discharges. The pump and valve elements of my engine are supported on a bracket 31, cast on the rear end of the 10 inner head of the engine cylinder *k*, as shown in Figs. I and III.

I claim:

1. In a device of the character described, the combination of a cylinder and piston 15 therein and a piston rod projecting through one end of the cylinder, a compensating chamber, a duct connecting that end of the cylinder through which the piston rod extends with said compensating chamber; a 20 fluid inlet for the compensating chamber, a valve in such inlet preventing the outflow of fluid; a force-pump, ducts connecting the latter with the compensating chamber and

the other end of the cylinder, an adjustable valve controlling the admission of fluid 25 through said ducts, and check valves in the latter.

2. In a device of the character described, the combination of a cylinder and piston 30 therein and a piston rod projecting through one end of the cylinder, a compensating chamber, a duct connecting that end of the cylinder through which the piston rod extends with said compensating chamber; a fluid inlet for the compensating chamber, a 35 valve in such inlet preventing the outflow of fluid; a force-pump, ducts connecting the latter with the compensating chamber and the other end of the cylinder, a four-way 40 adjustable valve controlling the admission of fluid through said ducts, and check valves in the latter.

FRANK E. KENNEY.
